IMAGE GENERATING APPARATUS

BACKGROUND OF THE INVENTION

1. Field of the Invention

The present invention relates to an image generating apparatus, and more particularly, it relates to an image generating apparatus comprising a light-emitting device emitting light for display.

2. Description of the Background Art

A switch or a button having a light-emitting device emitting light for display is known in general, as disclosed in Japanese Patent Laying-Open Nos. 09-282972 (1997), 05-307922 (1993), 2002-260479, 2005-84460 or 05-41134 (1993) for example. An image generating apparatus including such a switch or a button is known.

The aforementioned Japanese Patent Laying-Open No. 09-282972 discloses a push-button with an operational display having a structure in which a light-emitting device is set at the back of a center of a pressing surface as a light-emitting surface and the light-emitting surface and a set surface of the light-emitting device are arranged substantially parallel to each other, and capable of uniformly brightening the pressing surface (light-emitting surface) due to a uniform thickness of a light guide portion.

The aforementioned Japanese Patent Laying-Open No. 05-307922 discloses a lighting push-button switch in which a light-emitting diode (light-emitting device) is set below a center of a push-button switch top surface as a light-emitting surface and the push-button switch top surface and a set surface of the light-emitting diode are arranged substantially parallel to each other.

The aforementioned Japanese Patent Laying-Open No. 2002-260479 discloses a switch apparatus with a light in which a light source (light-emitting device) is set below a center of a holding sheet (light-emitting surface) and the holding sheet and a set surface of the light source are substantially parallel to each other.

The aforementioned Japanese Patent Laying-Open No. 2005-84460 discloses a button switch or the like having a structure in which a luminous body (light-emitting device) is set below a center of the light-emitting surface and the light-emitting surface and a set surface of the luminous body are arranged substantially parallel to each other, and capable of uniformly brightening the light-emitting surface due to diffusion of guided light by employing a light diffusing material in a light guide portion.

The aforementioned Japanese Patent Laying-Open No. 05-41134 discloses a lighting button apparatus having a structure in which a light-emitting diode (light-emitting device) is set below a center of a lighting portion (light-emitting surface) and the lighting portion and a set surface of the light-emitting diode are arranged substantially parallel to each other, and capable of diffusing incident light and uniformly brightening the lighting portion due to a Fresnel prism (prism having a saw-toothed section) provided on a rear surface (light incident surface) of the lighting portion.

In all sorts of the switches or the buttons described in the aforementioned Japanese Patent Laying-Open Nos. 09-282972, 05-307922, 2002-260479, 2005-84460 and 05-41134, however, the light-emitting surface and the set surface of the light-emitting device are arranged substantially parallel to each other, and hence it is disadvantageously difficult that the light-emitting surface is uniformly brightened in a structure in which the light-emitting surface is so arranged as to be inclined with respect to the set surface of the light-emitting device. Therefore, also when such a switch or

2

button is employed in an image generating apparatus having a structure in which the light-emitting surface of the switch or the button is so arranged as to be inclined with respect to the set surface of the light-emitting device, it is disadvantageously difficult that the light-emitting surface such as the switch of the image generating apparatus is uniformly brightened.

SUMMARY OF THE INVENTION

10 The present invention has been proposed in order to solve the aforementioned problem, and an object of the present invention is to provide an image generating apparatus having a structure in which a light-emitting surface is so arranged as to be inclined with respect to a set surface of a light-emitting device, capable of uniformly brightening the light-emitting surface.

An image generating apparatus according to a first aspect of the present invention comprises a light-emitting device emitting light for display, and a light guide member so arranged as to surround the light-emitting device and including a circumferential light-emitting surface and a circumferential light guide portion guiding the light emitted from the light-emitting device to the light-emitting surface, wherein the circumferential light-emitting surface is so arranged as to be inclined with respect to a surface on which the light-emitting device is set, and the circumferential light guide portion is formed such that a vertical thickness is substantially uniform with respect to the surface on which the light-emitting device is set.

In the image generating apparatus according to the first aspect, as hereinabove described, the circumferential light-emitting surface is so arranged as to be inclined with respect to the surface on which the light-emitting device is set, and the circumferential light guide portion is formed such that the vertical thickness is substantially uniform with respect to the surface on which the light-emitting device is set, whereby the light emitted from the light-emitting device can be guided to the light-emitting surface through the light guide portion having the uniform thickness and hence the light-emitting surface can be uniformly brightened also when the circumferential light-emitting surface is so arranged as to be inclined with respect to the set surface of the light-emitting device.

In the aforementioned image generating apparatus according to the first aspect, the light-emitting surface is preferably constituted by a first surface of the circumferential light guide portion, and the light guide portion is preferably formed such that the first surface constituting the light-emitting surface and a second surface on a side opposite to the first surface are substantially parallel to each other. According to this structure, the circumferential light guide portion can be easily formed such that the vertical thickness is substantially uniform with respect to the surface on which the light-emitting device is set.

55 In the aforementioned image generating apparatus according to the first aspect, at least the light-emitting surface of the light guide member preferably has a finely corrugated shape diffusing light. According to this structure, diffused light can be emitted on the light-emitting surface and hence the light-emitting surface can be uniformly brightened.

In this case, the light-emitting surface is preferably constituted by a first surface of the circumferential light guide portion, and an outer peripheral side surface of the circumferential light guide portion of the light guide member and a second surface on a side opposite to the first surface constituting the light-emitting surface each preferably have the finely corrugated shape diffusing light. According to this

structure, diffused light inside the light guide portion can be reflected on the outer peripheral side surface of the light guide portion and the second surface on the side opposite to the light-emitting surface, and hence the diffused light can be guided to the light-emitting surface. Consequently, the light-emitting surface can be further uniformly brightened.

In the aforementioned structure in which the light-emitting surface of the light guide member has the finely corrugated shape, at least an inner peripheral side surface of the circumferential light guide portion of the light guide member, upon which the light emitted from the light-emitting device is incident preferably has a flat surface shape without the finely corrugated shape diffusing light. According to this structure, light having reached the inner peripheral side surface of the light guide portion from the light-emitting device is not diffused and hence as much light as possible can be incident inside the light guide portion. Consequently, the light-emitting surface can be further brightened.

In the aforementioned image generating apparatus according to the first aspect, the light guide member preferably includes a dome portion having a light guide function, so provided inside the circumferential light guide portion as to be continuous to the light guide portion and cover the light-emitting device. According to this structure, the light guide member can guide light incident upon the dome portion from the light-emitting device to the light-emitting surface and hence the light-emitting surface can be further brightened.

In this case, the image generating apparatus preferably further comprises an infrared communication receiving portion provided in the vicinity of the light-emitting device for display, an infrared filter member so arranged as to cover the dome portion and having a filtering function capable of transmitting infrared ray while blocking visible light, and a reflective layer for reflecting the light from the light-emitting device, provided on a surface of the dome portion or a surface of the infrared filter member located between the dome portion and the infrared filter member. According to this structure, the reflective layer can inhibit light incident upon the dome portion from the light-emitting device from transmitting through the dome portion, and hence a larger amount of the light incident upon the dome portion can be guided to the light-emitting surface. Thus, the light-emitting surface can be further brightened.

In the aforementioned structure comprising the infrared communication receiving portion, the dome portion of the light guide member preferably has an opening for transmitting the infrared ray at a position opposed to the infrared communication receiving portion. According to this structure, an infrared signal can pass through the opening without blocking the same due to the light guide member and hence the infrared signal can reach the infrared communication receiving portion.

The aforementioned image generating apparatus according to the first aspect preferably further comprises a support portion movably supporting the light guide member in a pressing direction, and a switch portion arranged in the vicinity of the light-emitting device, wherein the light guide member preferably further includes a switch pressing portion arranged at a position opposed to the switch portion. According to this structure, the switch pressing portion can be pressed against the switch portion by pressing the light guide member and hence the light guide member can function as a press button.

In this case, the support portion preferably includes an arm portion so deflected as to be moved in a direction in which the switch pressing portion of the light guide member presses the switch portion by pressing the light guide member, and the

switch pressing portion is preferably so formed as to be moved in a direction for separating from the switch portion with restoring force of deflected the arm portion when press to the light guide member is released. According to this structure, the switch pressing portion can be easily pressed against the switch portion and the switch pressing portion can be easily separated from the switch portion when the press is released.

An image generating apparatus according to a second aspect of the present invention comprises a light-emitting device emitting light for display, a light guide member so arranged as to surround the light-emitting device and including a circumferential light-emitting surface and a circumferential light guide portion guiding the light emitted from the light-emitting device to the light-emitting surface, a support portion movably supporting the light guide member in a pressing direction, a switch portion arranged in the vicinity of the light-emitting device, an infrared communication receiving portion provided in the vicinity of the light-emitting device for display, an infrared filter member having a filtering function capable of transmitting infrared ray while blocking visible light, and a reflective layer for reflecting the light from the light-emitting device, wherein the light guide member further includes a dome portion having a light guide function and a switch pressing portion arranged at a position opposed to the switch portion, the circumferential light-emitting surface is so arranged as to be inclined with respect to a surface on which the light-emitting device is set, and constituted by a first surface of the circumferential light guide portion, the circumferential light guide portion is formed such that a vertical thickness is substantially uniform with respect to the surface on which the light-emitting device is set and the first surface constituting the light-emitting surface and a second surface on a side opposite to the first surface are substantially parallel to each other, the dome portion is so provided inside the circumferential light guide portion as to be continuous to the light guide portion and cover the light-emitting device, the infrared filter member is so arranged as to cover the dome portion, and the reflective layer is provided on a surface of the dome portion or a surface of the infrared filter member located between the dome portion and the infrared filter member.

In the image generating apparatus according to the second aspect, as hereinabove described, the circumferential light-emitting surface is so arranged as to be inclined with respect to the surface on which the light-emitting device is set, and the circumferential light guide portion is formed such that the vertical thickness is substantially uniform with respect to the surface on which the light-emitting device is set, whereby the light emitted from the light-emitting device can be guided to the light-emitting surface through the light guide portion having the uniform thickness and hence the light-emitting surface can be uniformly brightened also when the circumferential light-emitting surface is so arranged as to be inclined with respect to the set surface of the light-emitting device. The circumferential light-emitting surface is constituted by the first surface of the circumferential light guide portion, and the light guide portion is formed such that the first surface constituting the light-emitting surface and the second surface on the side opposite to the first surface are substantially parallel to each other, whereby the circumferential light guide portion can be easily formed such that the vertical thickness is substantially uniform with respect to the surface on which the light-emitting device is set. The light guide member further includes the dome portion having the light guide function, so provided as to be continuous to the circumferential light guide portion and cover the light-emitting device, whereby light

incident upon the dome portion from the light-emitting device can be guided to the light-emitting surface and hence the light-emitting surface can be further brightened. The image generating apparatus further comprises the reflective layer for reflecting the light from the light-emitting device, provided on the surface of the dome portion or the surface of the infrared filter member located between the dome portion and the infrared filter member so arranged as to cover the dome portion, whereby the reflective layer can inhibit light incident upon the dome portion from the light-emitting device from transmitting through the dome portion, and hence a larger amount of the light incident upon the dome portion can be guided to the light-emitting surface. Thus, the light-emitting emitting surface can be further brightened. The image generating apparatus further comprises the support portion movably supporting the light guide member in the pressing direction, and the switch portion arranged in the vicinity of the light-emitting device, wherein the light guide member includes the switch pressing portion arranged at the position opposed to the switch portion, whereby the switch pressing portion can be pressed against the switch portion by pressing the light guide member and hence the light guide member can function as a press button.

In the aforementioned image generating apparatus according to the second aspect, at least the light-emitting surface of the light guide member preferably has a finely corrugated shape diffusing light. According to this structure, diffused light can be emitted on the light-emitting surface and hence the light-emitting surface can be uniformly brightened.

In this case, the light-emitting surface is constituted by the first surface of the circumferential light guide portion, and an outer peripheral side surface of the circumferential light guide portion of the light guide member and a second surface on a side opposite to the first surface constituting the light-emitting surface each preferably have the finely corrugated shape diffusing light. According to this structure, diffused light inside the light guide portion can be reflected on the outer peripheral side surface of the light guide portion and the second surface on the side opposite to the light-emitting surface, and hence the diffused light can be guided to the light-emitting surface. Consequently, the light-emitting surface can be further uniformly brightened.

In the aforementioned structure in which the light-emitting surface of the light guide member has the finely corrugated shape, at least an inner peripheral side surface of the circumferential light guide portion of the light guide member, upon which the light emitted from the light-emitting device is incident preferably has a flat surface shape without the finely corrugated shape diffusing light. According to this structure, light having reached the inner peripheral side surface of the light guide portion from the light-emitting device is not diffused and hence as much light as possible can be incident inside the light guide portion. Consequently, the light-emitting surface can be further brightened.

In the aforementioned image generating apparatus according to the second aspect, the dome portion of the light guide member preferably has an opening for transmitting the infrared ray at a position opposed to the infrared communication receiving portion. According to this structure, an infrared signal can pass through the opening without blocking the same due to the light guide member and hence the infrared signal can reach the infrared communication receiving portion.

In the aforementioned image generating apparatus according to the second aspect, the support portion preferably includes an arm portion so deflected as to be moved in a direction in which the switch pressing portion of the light

guide member presses the switch portion by pressing the light guide member, and the switch pressing portion is preferably so formed as to be moved in a direction for separating from the switch portion with restoring force of deflected the arm portion when press to the light guide member is released. According to this structure, the switch pressing portion can be easily pressed against the switch portion and the switch pressing portion can be easily separated from the switch portion when the press is released.

The foregoing and other objects, features, aspects and advantages of the present invention will become more apparent from the following detailed description of the present invention when taken in conjunction with the accompanying drawings.

BRIEF DESCRIPTION OF THE DRAWINGS

20 FIG. 1 is a perspective view showing an overall structure of a dye sublimation printer according to an embodiment of the present invention;

25 FIG. 2 is a sectional view taken along the line 100-100 in FIG. 1;

FIG. 3 is a plan view showing the vicinity of display LEDs of the dye sublimation printer according to the embodiment of the present invention shown in FIG. 1;

30 FIG. 4 is a perspective view showing the vicinity of a power button of the dye sublimation printer according to the embodiment of the present invention shown in FIG. 1;

35 FIG. 5 is an exploded perspective view showing a structure of the vicinity of the power button of the dye sublimation printer according to the embodiment of the present invention shown in FIG. 1;

40 FIG. 6 is a plan view showing the vicinity of the power button of the dye sublimation printer according to the embodiment of the present invention shown in FIG. 1;

FIG. 7 is a sectional view taken along the line 200-200 in FIG. 6;

45 FIG. 8 is a plan view showing a light guide member of the dye sublimation printer according to the embodiment of the present invention shown in FIG. 1;

50 FIG. 9 is a side elevational view showing the light guide member of the dye sublimation printer according to the embodiment of the present invention shown in FIG. 1;

55 FIG. 10 is a sectional view showing the light guide member of the dye sublimation printer according to the embodiment of the present invention shown in FIG. 1;

FIG. 11 is an enlarged sectional view showing a finely corrugated portion of the light guide portion of the dye sublimation printer according to the embodiment of the present invention shown in FIG. 1;

60 FIG. 12 is a plan view showing a button support portion of the dye sublimation printer according to the embodiment of the present invention shown in FIG. 1;

FIG. 13 is a side elevational view showing the button support portion of the dye sublimation printer according to the embodiment of the present invention shown in FIG. 1;

65 FIG. 14 is a sectional view for illustrating a structure of the power button of the dye sublimation printer according to the embodiment of the present invention shown in FIG. 1; and

FIG. 15 is a sectional view for illustrating paths of passage of light emitting from the display LEDs of the dye sublimation printer according to the embodiment of the present invention shown in FIG. 1.

DESCRIPTION OF THE PREFERRED EMBODIMENTS

An embodiment of the present invention will be hereinafter described with reference to the drawings.

A structure of a dye sublimation printer according to the embodiment of the present invention will be now described with reference to FIGS. 1 to 14. This embodiment of the present invention is applied to the dye sublimation printer, which is an exemplary image generating apparatus.

The dye sublimation printer 1 according to this embodiment comprises a housing 10, a printing portion 20 (see FIG. 2) stored in the housing 10, a power button 30 arranged on a housing upper surface 10a, as shown in FIGS. 1 and 2. A paper cassette 50 storing a paper 40 is detachably mounted on a housing front surface 10b along arrow A of the housing 10. According to this embodiment, a portable telephone 60 having a camera function is supposed as an apparatus capable of infrared communication with the dye sublimation printer 1, as shown in FIG. 1.

As shown in FIGS. 1 and 2, the housing 10 is constituted by a housing rear surface 10c along arrow B, a housing lower surface 10d, a housing side surface 10e (see FIG. 1) along arrow C and a housing side surface 10f (see FIG. 1) along arrow D in addition to the aforementioned housing upper surface 10a and housing front surface 10b along arrow A. As shown in FIG. 2, the housing upper surface 10a is so formed as to be inclined with respect to a horizontal plane and has an opening 10g for mounting the power button 30 on an inclined surface. Protrusions (bosses) 10h for mounting the power button 30 on an inner surface in front of (along arrow A) the opening 10g are integrally provided on the housing upper surface 10a. A paper cassette receiving opening 10i for mounting the paper cassette 50 (see FIG. 1) is provided on the housing front surface 10b.

Four display LEDs 11 emitting light for display and an infrared receiving portion 12 capable of receiving an infrared signal from the portable telephone 60 (see FIG. 1) in the range of about 30° (about $\pm 15^\circ$) are arranged above the printing portion 20 in the housing 10. The display LED 11 is an example of the “light-emitting device” in the present invention. The four display LEDs 11 are arranged on a board 13 horizontally set, as shown in FIGS. 2 and 3. A switch portion 14 is arranged at a position surrounded by the four display LEDs 11 on the board 13 and electronic components 13a and 13b are arranged on sides along arrows C and D of the four display LEDs 11 respectively. As shown in FIG. 2, the infrared receiving portion 12 is arranged on a base plate 15 set in an upward direction at an angle of about 15° with respect to a horizontal direction (along arrow G). Thus, the infrared receiving portion 12 capable of receiving the infrared signal in the range of about 30° (about $\pm 15^\circ$) is capable of receiving the infrared signal in the range of about $\pm 15^\circ$ with respect to the upward direction at an angle of about 15° (range of about 30° upward from the horizontal plane) in a state where the housing 10 is horizontally set. Electronic components 15a, 15b and 15c are set at the back of the infrared receiving portion 12 (along arrow B) on the base plate 15. As shown in FIGS. 2 and 3, the base plate 15 is supported with a base plate pedestal 17 arranged on a base 16. The board 13 is set at the back of the base plate pedestal 17 (along arrow B) on an upper surface of the base 16 through leg portions 18 (see FIG. 2).

As shown in FIG. 2, the printing portion 20 has a bottom portion and side portions covered with a chassis 21 made of metal and is mountable with an ink sheet cartridge 22 storing an ink sheet 22a. The printing portion 20 includes a print head 23 for performing printing, a platen roller 24a so arranged as to be opposed to a print head 23, a feed roller 24b made of metal, a press roller 24c made of metal pressing the feed roller 24b with prescribed pressing force, a paper feed roller 24d made of rubber, a paper discharge roller 24e made of rubber, 10 a lower paper guide 25a made of resin, an upper paper guide 25b made of resin, an ink sheet cartridge support portion 26 supporting an ink sheet cartridge 22, a main board 27 and a top plate 28.

The chassis 21 is formed by a bottom surface 21a, a first 15 side surface (not shown) along arrow C in FIG. 1 and a second side surface 21b along arrow D. Pairs of mounting portions 21c for mounting the main board 27 are formed on upper ends of the first side surface (not shown) and the second side surface 21b respectively. The mounting portions 21c are provided with threaded holes 21d meshing with screws 29a for fixing the main board 27. The ink sheet cartridge 22 includes a take-up portion 22b taking up the ink sheet 22a, a supply portion 22c supplying the ink sheet 22a. The take-up portion 22b and the supply portion 22c of the ink sheet cartridge 22 25 have a take-up bobbin 22d and a supply bobbin 22e respectively. The main board 27 is mounted on the mounting portions 21c of the chassis 21 through the top plate 28. More specifically, the main board 27 is fixed by fastening four screws 29a passed through four holes 27a provided in the main board 27 and four holes 28a provided in the top plate 28 30 to the threaded holes 21d of the mounting portions 21c of the chassis 21. The base 16 is mounted at a position opposed to the opening 10g provided on the housing upper surface 10a on the upper surface of the main board 27 with two screws 29b. Thus, the four display LEDs 11, the switch portion 14 and the infrared receiving portion 12 are arranged at the position opposed to the opening 10g.

According to this embodiment, the power button 30 is constituted by an infrared filter member 31, a light guide member 32 and a button support portion 33, as shown in FIGS. 4 to 7. As shown in FIGS. 6 and 7, the power button 30 is so mounted on the opening 10g of the housing upper surface 10a (see FIG. 7) as to cover the display LEDs 11, the switch portion 14 and the infrared receiving portion 12. The button support portion 33 is an example of the “support portion” in the present invention.

The infrared filter member 31 has a dome shape and a filtering function capable of transmitting infrared ray while blocking visible light.

According to this embodiment, the light guide member 32 has a light-emitting surface 32a so formed circumferentially as to surround the display LEDs 11 (see FIG. 7) and a circumferential light guide portion 32b guiding light to the light-emitting surface 32a and a dome portion 32c having a light guide function, so provided inside the circumferential light guide portion 32b as to be continuous to the light guide portion 32b and cover the display LEDs 11, as shown in FIGS. 7 to 10.

According to this embodiment, the circumferential light-emitting surface 32a is inclined at an angle of a with respect to the horizontal plane such that the front side (side along arrow A) is lowered along the inclination of the housing upper surface 10a, as shown in FIG. 7. The circumferential light guide portion 32b is formed such that a first surface (upper surface) constituting a light-emitting surface 32a and a second surface constituting a lower surface 32d arranged on a side opposite to the first surface are substantially parallel to

each other. Thus, a thickness t in the vertical direction (along arrows E and F) of the circumferential light guide portion 32b is uniformly formed. In other words, the circumferential light guide portion 32b is formed such that the vertical thickness t is substantially uniformly formed with respect to a set surface of the display LEDs 11. In this case, a vertical distance $h1$ from a portion on the front side (side along arrow A) of the light guide portion 32b to the main board 27 horizontally set is shorter than a vertical distance $h2$ from a portion on the back side (side along arrow B) of the light guide portion 32b to the main board 27.

According to this embodiment, finely corrugated portions 32i diffusing light are formed on the light-emitting surface 32a, the lower surface 32d and an outer peripheral side surface 32e of the light guide portion 32b, as shown in FIG. 11. This enables emission of diffused light on the light-emitting surface 32a, and hence the light-emitting surface 32a can be uniformly brightened. Diffused light inside the light guide portion 32b can be reflected on the lower surface 32d and the outer peripheral side surface 32e, and hence diffused light can be guided to the light-emitting surface 32a. Thus, the light-emitting surface 32a can be further uniformly brightened. Light can be diffused on the lower surface 32d when light incident from the outside of the housing 10 is transmitted through the lower surface 32d, the inside of the housing 10 can be inhibited from observability from the outside of the housing 10 through the light guide portion 32b. The inner peripheral side surface 32j of the circumferential light guide portion 32b has a flat surface shape with no finely corrugated shape diffusing light. The dome portion 32c is formed in a dome shape along the dome-shaped infrared filter member 31.

According to this embodiment, the dome portion 32c is provided with a switch pressing portion 32f for pressing the switch portion 14 (see FIG. 7) when pressing the power button 30 (see FIG. 7) at a position opposed to the switch portion 14, as shown in FIGS. 7 and 10. A reflective layer 34 made of a white coating material having a function of reflecting light is formed on an outer surface 32g of the dome portion 32c for inhibiting light emitted from the display LEDs 11 (see FIG. 7) and incident inside the dome portion 32c from emitting from the outer surface 32g. The infrared filter member 31 is mounted on the outer surface 32g formed with the reflective layer 34 of the dome portion 32c with a double-faced adhesive tape (not shown). As shown in FIGS. 7 to 10, an opening 32h through which the infrared signal is passed is provided at a position opposed to the infrared receiving portion 12 of the dome portion 32c.

As shown in FIGS. 7, 12 and 13, the button support portion 33 is constituted by mounting portions 33a for mounting the protrusions 10h of the housing upper surface 10a (see FIG. 7), a ring portion 33c formed with an inner peripheral surface 33b to be contact with the outer peripheral side surface 32e of the light guide portion 32b (see FIG. 7) and arm portions 33d coupling the mounting portions 33a and the ring portion 33c. The mounting portions 33a has receiving holes 33e capable of receiving (being press-fitted around) the protrusions 10h. As shown in FIG. 7, the protrusions 10h is lightly press-fitted into the receiving holes 33e so that the mounting portions 33a has an upper portion mounted on the housing upper surface 10a and a lower surface in contact with an upper surface of the top plate 28. Thus, the mounting portions 33a of the button support portion 33 are fixed. The ring portion 33c has a L-shaped receiving portion 33f preventing the light guide member 32 from slipping off on a lower portion of the inner peripheral surface 33b. As shown in FIG. 5, the power button 30 is assembled by inserting the light guide member 32 mounted

with the infrared filter member 31 into the ring portion 33c along arrow F. The arm portions 33d have first ends fixed on upper ends of the mounting portions 33a and second ends fixed on a lower surface of the ring portion 33c. In other words, the assembled power button 30 is supported with the fixed arm portions 33d extending from the mounting portions 33a. More specifically, the power button 30 fixed with the mounting portions 33a of the button support portion 33 is movably supported in a pressing direction (along arrow F) by deflecting the arm portions 33d relative to the first ends closer to the mounting portions 33a of the arm portions 33d with pressing force P along arrow F, as shown in FIG. 14. Thus, the arm portions 33d are deflected relative to the first ends closer to the mounting portions 33a when the power button 30 is pressed along arrow F, and hence the switch pressing portion 32f provided on the light guide member 32 moves in the pressing direction to press the switch portion 14. When the pressing force P is released, the switch pressing portion 32f moves upward, i.e. in a direction for separating from the switch portion 14 with upward urging force (restoring force) of the deflected arm portions 33d and the power button 30 is reset at an original position.

Paths of passage of light emitting from the display LEDs 11 of the dye sublimation printer 1 according to the embodiment 25 of the present invention will be described with reference to FIG. 15.

As shown in FIG. 15, the light emitting from the display LEDs 11 is applied to an inner surface of the dome portion 32c of the light guide member 32 and the inner peripheral side 30 surface of the light guide portion 32b. Light applied to the inner surface of the dome portion 32c and incident inside the dome portion 32c is reflected with the reflective layer 34 of the outer surface 32g. The reflected light reaches the light-emitting surface 32a through the inside of the dome portion 32c while being repeatedly reflected on the inner surface and the outer surface 32g. Light applied to the inner peripheral side surface of the light guide portion 32b and incident inside of the light guide portion 32b reaches the light-emitting surface 32a through the inside of light guide portion 32b while being repeatedly reflected on the lower surface 32d, the outer peripheral side surface 32e and the inner peripheral side surface. At this time, the light is diffused to be reflected by the finely corrugated portions 32i of the lower surface 32d and the outer peripheral side surface 32e. Then the light having reached the light-emitting surface 32a of the light guide member 32 is emitted from the light-emitting surface 32a while being diffused by the finely corrugated portions 32i of the light-emitting surface 32a and the light-emitting surface 32a is brightened.

According to this embodiment, as hereinabove described, the circumferential light-emitting surface 32a is so arranged as to be inclined with respect to the board 13 (horizontal plane) where the display LEDs 11 are set, and the circumferential light guide portion 32b is formed such that the vertical thickness t is substantially uniform with respect to the board 13 where the display LEDs 11 are set, whereby the light emitted from the display LEDs 11 can be guided to the light-emitting surface 32a through the light guide portion 32b having the uniform thickness t and hence the light-emitting surface 32a can be uniformly brightened also when the circumferential light-emitting surface 32a is so arranged as to be inclined with respect to the set surface of the display LEDs 11.

According to this embodiment, the light-emitting surface 32a is constituted by the first surface of the circumferential light guide portion 32b, and the light guide portion 32b is formed such that the first surface constituting the light-emitting surface 32a and the second surface constituting the lower

11

surface 32d arranged on the side opposite to the first surface are substantially parallel to each other, whereby the circumferential light guide portion 32b can be easily formed such that the vertical thickness t is substantially uniform with respect to the board 13 where the display LEDs 11 are set.

According to this embodiment, the light guide member 32 is provided with the dome portion 32c having the light guide function, so provided inside the circumferential light guide portion 32b as to be continuous to the light guide portion 32b and cover the display LEDs 11, whereby the light guide member 32 can guide the light incident upon the dome portion 32c from the display LEDs 11 to the light-emitting surface 32a and hence the light-emitting surface 32a can be further brightened.

According to this embodiment, the reflective layer 34 for reflecting the light from the display LEDs 11 is provided on the outer surface 32g of the dome portion 32c located between the dome portion 32c and the infrared filter member 31 arranged to cover the dome portion 32c, whereby the reflective layer 34 can inhibit the light incident upon the dome portion 32c from the display LEDs 11 from transmitting through the dome portion 32c, and hence a larger amount of the light incident upon the dome portion 32c can be guided to the light-emitting surface 32a. Thus, the light-emitting surface 32a can be further brightened.

According to this embodiment, the inner peripheral side surface 32j of the circumferential light guide portion 32b of the light guide member 32 upon which the light emitted from the display LEDs 11 is incident is so formed in the flat surface shape with no finely corrugated shape diffusing light, whereby the light having reached the inner peripheral side surface 32j of the light guide portion 32b from the display LEDs 11 is not diffused and hence as much light as possible can be incident inside the light guide portion 32b.

According to this embodiment, the arm portions 33d deflected to be moved in the direction in which the switch pressing portion 32f of the light guide member 32 presses the switch portion 14 by pressing the light guide member 32 is provided in the button support portion 33, and the switch pressing portion 32f is so formed as to be moved in the direction for separating from the switch portion 14 with restoring force of the deflected arm portions 33d when the press to the light guide member 32 is released, whereby the switch pressing portion 32f can be easily pressed against the switch portion 14 and the switch pressing portion 32f can be easily separated from the switch portion 14 when the press is released.

Although the present invention has been described and illustrated in detail, it is clearly understood that the same is by way of illustration and example only and is not to be taken by way of limitation, the spirit and scope of the present invention being limited only by the terms of the appended claims.

For example, while the aforementioned embodiment is applied to the dye sublimation printer employed as an example of the image generating apparatus, the present invention is not restricted to this but is also applicable to an image generating apparatus other than the dye sublimation printer, so far as the image generating apparatus comprises the light-emitting device emitting light for display.

While the finely corrugated portion diffusing light is formed on the lower surface of the light guide portion in order to inhibit the inside of the housing from observability from the outside of the housing in the aforementioned embodiment, the present invention is not restricted to this but a sheet for inhibiting the inside of the housing from observability from the outside of the housing may be alternatively mounted.

12

While the reflective layer made of the white coating material is formed on the outer surface of the dome portion in the aforementioned embodiment, the present invention is not restricted to this but a similar reflective layer may be alternatively formed on the inner surface of the infrared filter member or a sheet reflecting light in place of the reflective layer made of the coating material may be alternatively arranged between the infrared filter member and the dome portion of the light guide member.

While the portable telephone is shown as an apparatus capable of infrared communication in the aforementioned embodiment, the present invention is not restricted to this but an apparatus capable of infrared communication other than the portable telephone may be alternatively employed.

What is claimed is:

1. An image generating apparatus comprising:
a light-emitting device emitting light for display; and
a light guide member so arranged as to surround said light-emitting device and including a circumferential light-emitting surface and a circumferential light guide portion guiding the light emitted from said light-emitting device to said light-emitting surface, wherein
said circumferential light-emitting surface is constituted by a first surface of said circumferential light guide portion and is so arranged as to be inclined with respect to a device set surface on which said light-emitting device is set,
said circumferential light guide portion is formed such that a vertical thickness is substantially uniform with respect to said device set surface and is formed such that said first surface constituting said light-emitting surface and a second surface on a side opposite to said first surface are substantially parallel to each other, and
a height of a front part of said second surface from said device set surface in the vertical direction with respect to said device set surface is lower than a height of a rear part of said second surface from said device set surface.
2. The image generating apparatus according to claim 1, wherein
at least said light-emitting surface of said light guide member has a finely corrugated shape diffusing light.
3. The image generating apparatus according to claim 2, wherein
said light-emitting surface is constituted by a first surface of said circumferential light guide portion, and
an outer peripheral side surface of said circumferential light guide portion of said light guide member and a second surface on a side opposite to said first surface constituting said light-emitting surface each have said finely corrugated shape diffusing light.

4. The image generating apparatus according to claim 2, wherein
at least an inner peripheral side surface of said circumferential light guide portion of said light guide member upon, which the light emitted from said light-emitting device is incident has a flat surface shape without said finely corrugated shape diffusing light.

5. The image generating apparatus according to claim 1, wherein
said light guide member further includes a dome portion having a light guide function, so provided inside said circumferential light guide portion as to be continuous to said light guide portion and cover said light-emitting device.
6. The image generating apparatus according to claim 5, further comprising:

13

an infrared communication receiving portion provided in the vicinity of said light-emitting device for display; an infrared filter member so arranged as to cover said dome portion and having a filtering function capable of transmitting infrared ray while blocking visible light; and a reflective layer for reflecting the light from said light-emitting device, provided on a surface of said dome portion or a surface of said infrared filter member located between said dome portion and said infrared filter member.

7. The image generating apparatus according to claim 6, wherein

said dome portion of said light guide member has an opening for transmitting said infrared ray at a position opposed to said infrared communication receiving portion.

8. The image generating apparatus according to claim 1, further comprising:

a support portion movably supporting said light guide member in a pressing direction; and

a switch portion arranged in the vicinity of said light-emitting device, wherein

said light guide member further includes a switch pressing portion arranged at a position opposed to said switch portion.

9. The image generating apparatus according to claim 8, wherein

said support portion includes an arm portion so deflected as to be moved in a direction in which said switch pressing portion of said light guide member presses said switch portion by pressing said light guide member, and said switch pressing portion is so formed as to be moved in a direction for separating from said switch portion with restoring force of deflected said arm portion when press to said light guide member is released.

10. An image generating apparatus comprising:

a light-emitting device emitting light for display; a light guide member so arranged as to surround said light-emitting device and including a circumferential light-emitting surface and a circumferential light guide portion guiding the light emitted from said light-emitting device to said light-emitting surface;

a support portion movably supporting said light guide member in a pressing direction;

a switch portion arranged in the vicinity of said light-emitting device;

an infrared communication receiving portion provided in the vicinity of said light-emitting device for display; an infrared filter member having a filtering function capable of transmitting infrared ray while blocking visible light; and

a reflective layer for reflecting the light from said light-emitting device, wherein

said light guide member further includes a dome portion having a light guide function and a switch pressing portion arranged at a position opposed to said switch portion,

14

said circumferential light-emitting surface is so arranged as to be inclined with respect to a surface on which said light-emitting device is set, and constituted by a first surface of said circumferential light guide portion,

5 said circumferential light guide portion is formed such that a vertical thickness is substantially uniform with respect to said surface on which said light-emitting device is set and said first surface constituting said light-emitting surface and a second surface on a side opposite to said first surface are substantially parallel to each other,

said dome portion is so provided inside said circumferential light guide portion as to be continuous to said light guide portion and cover said light-emitting device, said infrared filter member is so arranged as to cover said dome portion, and

said reflective layer is provided on a surface of said dome portion or a surface of said infrared filter member located between said dome portion and said infrared filter member.

20 11. The image generating apparatus according to claim 10, wherein

at least said light-emitting surface of said light guide member has a finely corrugated shape diffusing light.

25 12. The image generating apparatus according to claim 11, wherein

an outer peripheral side surface of said circumferential light guide portion of said light guide member and a second surface on a side opposite to said first surface constituting said light-emitting surface each have said finely corrugated shape diffusing light.

30 13. The image generating apparatus according to claim 11, wherein

at least an inner peripheral side surface of said circumferential light guide portion of said light guide member, upon which the light emitted from said light-emitting device is incident has a flat surface shape without said finely corrugated shape diffusing light.

35 14. The image generating apparatus according to claim 10, wherein

said dome portion of said light guide member has an opening for transmitting said infrared ray at a position opposed to said infrared communication receiving portion.

40 15. The image generating apparatus according to claim 10, wherein

said support portion includes an arm portion so deflected as to be moved in a direction in which said switch pressing portion of said light guide member presses said switch portion by pressing said light guide member, and

said switch pressing portion is so formed as to be moved in a direction for separating from said switch portion with restoring force of deflected said arm portion when press to said light guide member is released.
